O. W. SCHAUZ,
PHONOGRAPH ATTACHMENT,
APPLICATION FILED MAY 11, 1918.

1,283,571.

Patented Nov. 5, 1918.

Inventor:
Oscar W. Schauz,
By Almon Hall, Atty.

UNITED STATES PATENT OFFICE.

OSCAR WM. SCHAUZ, OF ADRIAN, MICHIGAN.

PHONOGRAPH ATTACHMENT.

1,283,571.

Specification of Letters Patent. Patented Nov. 5, 1918.

Application filed May 11, 1918. Serial No. 233,858.

To all whom it may concern:

Be it known that I, OSCAR WILLIAM SCHAUZ, a citizen of the United States, residing at Adrian, (227 Michigan St.) in the county of Lenawee and State of Michigan, have invented certain new and useful Improvements in Phonograph Attachments; and I do declare the following to be a full, clear, and exact description of the invention, such as will enable others skilled in the art to which it appertains to make and use the same, reference being had to the accompanying drawings, and to the letters and figures of reference marked thereon, which 15 form a part of this specification.

My invention relates to a device for amplifying the tone of a phonograph, and for rendering more distinct the annunciation in phonographic reproductions, as well as for 20 reducing the usual annoying scratching effect accompanying such reproductions.

To these ends my invention consists of the devices, construction and arrangement of parts hereinafter described, and illustrated 25 in the accompanying drawings in which,—

Figure 1 is a front elevation of my device; Fig. 2 a side elevation of one of the halves of my device, seen from its inner side, and Fig. 3 is a top plan view of my 30 device.

Like numerals of reference indicate like parts throughout the several views.

My device consists of a structure composed of a block made, preferably, of flat 35 strips of wood boards, built up and glued or otherwise rigidly and closely joined together to constitute substantially a solid block of approximately the contour, in side elevation, illustrated in Fig. 2 and in front 40 elevation in Fig. 1. I prefer, for convenience of manufacture, to divide the block vertically into two equal parts as shown by the dividing lines in the drawings, the halves being secured together face to face by bolts, 45 as shown, or in any other suitable manner.

The flat top 1 of my device is designed to be secured to the under side of the sounding board of a phonograph, directly beneath the foot of the pedestal of the needle carrying 50 arm. The mouth 2 of the device is turned to the front of the phonograph. This mouth in outline is rectangular, and is adapted to receive the smaller end of a phonograph-horn of the usual or any preferred construction.

Through the block, from its top to its mouth, extends a sound passage 3, the walls of which and their conformation and relation to each other constitute the principal feature of my invention. Beginning at the 60 top, the opening is circular in outline. From this top to the line *a* the passage flares slightly, and assumes in outline a slightly elliptical form, the major axis of which ellipse extends from side to side of the passage. From the line *a* to the line *b* the passage continues to widen both vertically and horizontally in such a fashion that here the cavity has assumed a substantially spherical form. From the line *b* the passage 70 turns upwardly and forwardly in a horizontal direction, gradually narrowing vertically and widening horizontally into a passage, rectangular in cross-section, as illustrated at the mouth 2 of the passage. The 75 cross-sectional area of the passage 3 increases in a constant ratio from inlet to outlet.

Through the block near its upper end may be a thin horizontal slot 4 adapted for the 80 reception of a thin flat slide which may be employed to partly or wholly reduce the volume of sound traversing the passage 3.

The theory which I entertain as to the specific effect of the sound passage, shaped 85 as above described, upon sound waves during their passage through the instrument, is largely speculative and, being incapable of demonstration, need not be here elaborated. Practical employment of the device here 90 described does, however, demonstrate that a sound passage, having the several successive contours described,—which contours have been determined after many long and careful experiments,—do amplify and define the tones and sounds in phonographic 95 reproductions, and that they do largely eliminate the unpleasant "scratchy" effect usually accompanying the tones of a phonograph.

Having described my invention, what I claim and desire to secure by Letters Patent is—

1. In a device of the described character, a block having therethrough and leading 105 downwardly from its top a sound passage of constantly increasing area in cross-section, which passage from its lower part curves upwardly and forwardly, such passage,—including such curve,—being curvi-

linear in transverse outline, circular at its inlet and which, at its outlet, merges into rectangular transverse outline.

2. A device of the described character, comprising a body adapted for attachment in a phonograph, said body having therethrough, leading from its top, a passage of gradually increasing area in cross-section from inlet to outlet, said passage being circular at its top, then widening to an ellipse,

then widening to a substantially spherical chamber, then curving upwardly and horizontally and terminating in rectangular cross-section.

In testimony whereof I affix my signature 15 in presence of two witnesses.

OSCAR WM. SCHAUZ.
